GUMMING MACHINE

Arthur Bennett, San Francisco, Calif.

Application April 6, 1935, Serial No. 15,005

10 Claims. (Cl. 154—1)

This invention relates to gummed tape and strips and the application of such strips to sheets of paper and the like, and the objects of the invention are to provide suitable apparatus 5 to facilitate the application of gummed strips to paper sheets, also for dampening the gummed strips preparatory to their application to the sheets, and also for coating the tapes with the gum in applying them to the sheets. Other features and advantages of the invention will appear in the following description and accompanying drawings.

In the drawings Fig. 1 is an isometric view of my improved gum strip applying table or apparatus.

Fig. 2 is an enlarged view of the right-hand forward corner of the table of Fig. 1 showing the moistening device, tape back stop and cut-off blade.

Fig. 3 is an enlarged side elevation of the cut-off blade operating hook-up.

Fig. 4 is an enlarged plan view of the angular guide bar for reversing the moistened tape.

Fig. 5 is an elevation of Fig. 4.

Fig. 6 is an enlarged vertical section showing the paper stack holding finger and associated parts.

Fig. 7 is a still further enlarged side elevation of the paper stack holding finger.

Fig. 8 is a front elevation of the right-hand forward corner of the table with a gum applying fountain in place over the tape.

Fig. 9 is an enlarged elevation partly in section showing the construction of the nozzle of the gum applying fountain.

Fig. 10 is an end view of Fig. 9 showing the gum exuding slot in the nozzle.

Fig. 11 is a vertical section of the tape moistening pad.

Briefly described, the invention comprises apparatus to facilitate applying strips of gummed tape along opposite margins of sheets of paper such as printed sheets, signs, posters, etc., which are later to be stuck to show windows, walls, etc., for temporary display. The type of gummed tape for which the apparatus was particularly designed to handle is that which is always tacky and may be transferred bodily from the tape on which it is coated to the margin of a printed poster or the like, the tape being stripped off when it is desired to apply the poster to the show window, the ever-tacky gum left on the poster sufficing to stick the same to the window. Such a tape and the ingredients for the special gum used is fully described in my

copending patent application filed under Serial No. 13,037 on date of March 26, 1935, though it is to be understood that the present apparatus is also useful for applying other or any kind of gummed tape or strips to the margins, or other portions of printed or unprinted sheets of paper or other material.

In further detail the drawings show a table 1 supported on a frame 2, provided with a foot treadle 3 at the front of the table for operating 10 certain features of the apparatus to be described. The table top is adapted to support a pile or stack of sheets 4 aligned along one side by a strip or straight edge 5, and at the rear by a block 6 adjustably clamped to the 15 strip 5, while on top of the stack of sheets, which may be printed posters or the like, is a heavy weight 7 provided with a handle 8, and a forwardly extending rod or finger 9 which overlies the upturned forward edges 4' of the 20 paper sheets and holds them in the position shown in Figs. 1 and 2. This finger is adjustably pivoted and clamped to the weight 7 as at 10 so that it may be set for any size stack 25 of sheets desired and its outer end is curved downwardly and provided with a small notch as at 11 or slightly hooked extremity so that one sheet of the paper at a time may be easily and quickly released from engagement with the finger by the friction of an operator's fingers on the forward (or bottom) sheet and whereupon said sheet will fall to bridge a gap 12 in the table and rest with its forward margin on the forward portion or rail 1' of the table and along which the gummed tape 13 has previously been 30 laid so that the sheet will fall upon it.

The tape used may be some which has previously been coated with gum and rolled up, or it may be coated initially with the gum on this apparatus. If the already prepared tape is used, 40 a roll 14 of it is placed over a spindle 15 on a shelf 16 extending from the side of the table and the tape is led from the roll over a standing spindle or post 17 to hold the tacky side of the tape 13 outward, thence the tape passes forwardly along the margin of the table, is twisted at 13' to turn its tacky side up, thence passed downward over idler roll 18, twisted again, passed around a tension roller 19, thence upward and twisted again and over a second idler roll 20, 50 again twisted to turn its tacky side down and passed over a moistening pad 21 where it is moistened with any liquid which will act as a solvent for the particular gum on the tape—such as gasoline for the tacky rubber compound gum 55

disclosed in my copending application before mentioned—and, after moistening, the tape is reversed around an angularly positioned roll or rod 22 to bring its moistened and now more tacky 5 side uppermost and also change its direction of travel 90° so that it may be pulled along the inner margin of table rail 1' adjacent gap 12 and one of the paper sheets 4 released from finger 9 will fall upon its sticky surface, and after which 10 the tape is cut off in line with the right-hand edge of the sheet by means of a blade 23 operated by the foot treadle 3.

Blade 23 is pivoted to a shear block 24 secured to the rail 1' of the table, and the shank of the 15 blade is linked at 25 to a bell crank 26 pivoted at 27 to the frame of the table and which crank is connected to the treadle as by a chain 28 provided with a turnbuckle 29 so that the cutting stroke of the blade may be accurately determined. 20 A stop screw 56 is also provided to limit the descent of the blade. The treadle is normally raised by a tension spring 30.

The moistening pad 21 may take various forms but is here indicated as a small tray through 25 which the tape passes face down under a guide 53, while under the tape is a felt pad or brush 54, and the tape arranged to touch it as it goes along to moisten the gummed surface of the tape and increase its tackiness, though it may be 30 here stated that the ever-tacky tape of my copending case will work without this moistening, but takes a little more time and pressure to get equal adherence to the printed posters or sheets. As stated, the lubricant for tape coated with 35 rubber compound gum is gasoline or similar solvent, and it is better to have it mixed with some fireproof solvent such as carbon tetrachloride. The pad tray is kept supplied to a shallow depth with the solvent from an inverted supply can 31 or one fitted with a tight closure on top 40 and open through a feed tube 32 at the bottom which projects into the liquid in the tray in the common manner of a poultry drinking fountain. The raising or lowering of the feed tube to determine the depth is controlled by a set collar 33.

When the tape is cut off by blade 23 it is automatically clamped to prevent its pulling back or curling. This is done by a pivotally mounted block or back stop 34 under which the tape is 50 pulled and which block has one or more small spurs or impinging edge 35 on its lower side which is forced against the tape by the weight of the block swinging on its pivot 36 yet due to the cam-like pivoting of the block it permits the tape to be freely drawn forwardly under the block. Fig. 5 illustrates this action clearly.

After dropping one sheet upon a stretch of the moistened tacky tape and cutting it off, a fresh length of tape is drawn along the rail right on 60 top of the previous fallen sheet and the next sheet is dropped from the stack to this strip of tape to stick to it, and so on until several are thus superimposed and after which they are pushed bodily through the table gap to spring 65 below it as indicated in Fig. 6 so that they can dry more easily, and/or will be out of the way of continued operations.

An adjustable stop gage 31 is provided on the inner edge of the table rail 1' to align the outer 70 end of the tape with the edge of the sheet of paper. As the tacky tape requires quite a pull to release it from the supply roll 14 and which would impede the speed of operation of applying the tapes to the sheets, the foot treadle is 75 arranged to unwind a new length each time it

is depressed, and to achieve this, tension roller 19 is mounted in a carriage 38 which slides vertically on a pair of guide rods 39 and the carriage is linked at 40 to the end of an arm 41 extending transversely under the table and pivoted at its other end to the table frame as at 42, and which arm is pulled upwardly by a light tension spring 43 to just about counterbalance its weight and the weight of the carriage 38 and its roller 19 so that each time a length of tape is 10 pulled along the rail for another sheet of paper, the tension or take-up carriage will rise with little or no resistance to supply the length of tape needed, and is forcibly pulled down again by the 15 foot treadle when operating the cutting off blade, through means of a chain connection 44. Thus the power of the foot is used each time to unwind a new length of the tacky tape from the roll, and the operator needs use but slight effort to pull the tape to position along the rail of 20 the table.

Instead of using previously prepared tacky tape, the tape may be coated on this apparatus and directly applied to the poster sheets by substituting a gum coating fountain 45 for the 25 dampening fountain and using a roll 46 of plain uncoated tape supported on a bracket 47 (which may be shelf 16) attached to the side of the table so that the tape can run straight from it and along the rail 1'. This is shown in Fig. 8 with 30 details of the gumming nozzle in Figs. 9 and 10. In this arrangement the tape 48 runs over a guide pin 57, thence under the back stop 34, and thence under the nozzle 49 of the gum fountain, thence over the shearing block 24 and along the 35 rail as previously described.

In Fig. 8 the cutting off blade 23 is shown as descended and about to cut off the tape.

The gum fountain is a can containing the fluid gum compound of about the consistency of glue or rubber cement, and it flows by gravity into 40 the nozzle 49 which is an elongated housing the width of the tape and provided with an under-cover 50 pivoted to it as at 51 and resiliently held upward by a light tension spring 52 so as to 45 gently hold the tape against the relatively thick or wide edges of the nozzle as it slides along and thus keep opposite margins of the tape bare of gum. This cover is channel-shaped and its sides 50' extend up along both sides of the nozzle as best shown in Fig. 10, and at the tape-leaving end 50 of the nozzle the end wall is relieved a trifle as at 55 so as to provide a clearance above the tape, and it is the size of this clearance which determines the thickness of the layer of adhesive gum compound deposited on the tape as it is pulled 55 through and drawn along the rail to receive a sheet 4' of paper from the pile.

With this arrangement the freshly coated tape is applied to the paper sheets and it requires no moistening. Owing to the very small clearance 60 for the gum to flow from the nozzle and the adhesive nature of the gum, it will not flow out objectionably when the tape is at rest.

In operation, as each length of tape is pulled out along the table, or with tacky face up upon 65 the previously taped sheet still in place so as to receive the next sheet, the finger is gently rubbed along the sheet below to insure a good contact of the previously applied tape and sheet, or this 70 may be done on the return stroke of the hand in moving back to pull the tape again. If plain tacky tape is used with no moistening it will have to be pressed very firmly into contact with the sheets, either with the fingers, a roller, or scraper. 75

Any size sheets may be handled on the table by suitable adjustment of its guides and stops 5, 6 and 37. Also tape of any desired material may be used in the apparatus, such as cloth, 5 paper, Cellophane, or any other flexible material, and the adhesive coating may be of any nature or quality desired, and the tape may be placed at any desired position on the sheets, either at one or opposite margins, and/or in any other 10 position on the sheets by suitably adjusting the position of the sheets relative to the tape.

Having thus described my improved apparatus and the manner of its use, what I claim is:

1. Apparatus of the character described comprising a supporting surface, means supporting a roll of tape for drawing its free end along and positioning a length of the tape on said surface, and means for supporting and guiding separate cut sheets of paper to position one at a time 20 respectively with one margin overlying successive lengths of tape so positioned on said surface.

2. Apparatus of the character described comprising a supporting surface, means supporting a roll of tape for drawing along and positioning 25 on said surface, means for guiding a sheet of paper to position against said tape on said surface, the last-mentioned means including means holding down a pile of paper sheets, and means arranged to hold one end of the pile arched up 30 wardly so that the sheets may be released in succession to fall to position.

3. Apparatus of the character described comprising a supporting surface, means supporting a roll of tape for drawing along and positioning 35 on said surface, means for guiding a sheet of paper to position against said tape on said surface, the last-mentioned means including means holding down a pile of paper sheets, a finger arranged to hold one end of the pile arched up 40 wardly so that the sheets may be released in succession to fall to position, and a gap in said surface straddled by said sheets in falling, said tape being supported on the surface beyond said gap or remote from said pile of paper.

4. In a structure as specified in claim 2, said "means holding down a pile of paper sheets" being a weight block and said finger being adjustably secured to said weight block.

5. In a structure as specified in claim 2, said "means holding down a pile of paper sheets" being a weight block and said finger being adjustably secured to said weight block and provided with a slightly hooked outer end adapted to let go one sheet of paper at a time upon the application of gentle force to the sheets.

6. Apparatus of the character described comprising a work-supporting table adapted to support a pile of paper sheets to be taped at their margins, means supporting a roll of adhesive tape for pulling along the table to position thereon relative to said sheets, a take-up carriage

over which the tape from said roll is extended, a back stop device active on said tape to prevent backward movement after a length has been pulled from the roll, a manually operated blade for cutting off the tape, and manually operated 5 means for operating said take-up carriage to pull a length of the tape from said roll.

7. Apparatus of the character described comprising a work-supporting table adapted to support a pile of paper sheets to be taped at their 10 margins, means supporting a roll of adhesive tape for pulling along the table to position thereon relative to said sheets, a take-up carriage over which the tape from said roll is extended, a back stop device active on said tape to prevent back- 15 ward movement after a length has been pulled from the roll, a foot treadle operated blade arranged for cutting off lengths of the tapes pulled from said roll, and means connecting said take-up carriage for operation by said treadle for pulling a length of tape from said roll each time the treadle is depressed.

8. In a construction as specified in claim 7, said take-up carriage being of the gravity type and provided with counterbalancing means so 25 that it will move with slight effort as the tape is pulled.

9. Apparatus for applying gummed tape to the margins of separate paper sheets which comprises means for supporting a stack of superimposed sheets of paper, a supporting surface along which a strip of sticky gummed tape is adapted to be laid sticky side up adjacent said sheets, means for holding the supported sheets bent backward and upward and adapted for releasing 35 of the sheets one at a time to fall respectively at one margin each upon successive strips of sticky tape superimposed on the margins of the sheets above the tape laid on said supporting surface, and whereby the sheets may be firmly 40 united to the tapes by pressure along the margin overlying the tape.

10. Apparatus for applying gummed tape to the margins of separate paper sheets which comprises means for supporting a stack of superimposed sheets of paper, a supporting surface along which a strip of sticky gummed tape is adapted to be laid sticky side up adjacent said sheets and separated from the sheet supporting means by a gap, means for holding the supported sheets bent backward and upward and adapted for releasing of the sheets one at a time to fall respectively at one margin each upon successive strips of sticky tape laid on said supporting surface, whereby the sheets may be firmly united to the tapes by pressure along the margin overlying the tape, and said gap being arranged and adapted for pushing the taped sheets through as they are finished.

ARTHUR BENNETT. 60
